S. M. ISRAEL

ADJUSTABLE SUPPORT FOR ELECTRIC LIGHT CANDLES

Filed Aug. 22, 1923

Inventor:
Sidney M. Israel,
By his Attorney,
Geo. W. Mait

UNITED STATES PATENT OFFICE.

SIDNEY M. ISRAEL, OF WOODHAVEN, NEW YORK.

ADJUSTABLE SUPPORT FOR ELECTRIC-LIGHT CANDLES.

Application filed August 22, 1923. Serial No. 658,744.

To all whom it may concern:

Be it known that I, SIDNEY M. ISRAEL, a citizen of the United States, and a resident of Woodhaven, county of Queens, city 5 and State of New York, have invented certain new and useful Improvements in Adjustable Supports for Electric-Light Candles, of which the following is a specification, sufficient to enable those skilled in the 10 art to which the invention appertains to utilize the same.

My invention relates to the class of electric light fixtures designated in my concurrent application Serial No. 612,928, filed 15 January 16, 1923, which are intended to simulate the use of candles; and my improvements are designed to afford a simple, inexpensive, but effective and substantial support for an incandescent candle lamp 20 bulb, by means of which said lamp bulb may be conveniently adjusted as related to the other parts of the fixture, all as hereinafter fully set forth,—the invention, to this end, consisting in the specific construction, combination and arrangement of parts 25 described and claimed, whereby, the manipulation thereof is facilitated and rendered effective.

In the accompanying drawings I exemplify a practical embodiment of the essential features of my invention in an adjustable lamp support consisting of a one-piece basic section and a one-piece extension section, each of said sections being 30 made from a blank of sheet metal, die-formed and bent into the requisite shapes, with interlocking parts as related to each other, although I do not limit myself to the identical configuration and construction 35 thereof shown, since modifications in minor details and mechanical expedients may be resorted to with like result, and without departing from the spirit and intent of my invention in this respect.

With this understanding;

Fig. 1, represents a flat view of the metallic blank used in the formation of the adjustable section of my lamp support; and

Fig. 2, what may be designated as a front 50 view of said adjustable section bent into requisite shape;

Fig. 3, is an upper end elevation of the part shown in Fig. 2;

Fig. 4, is a lower end elevation thereof;

Fig. 5, represents a flat view of the metal-

lic blank used in the formation of the basic section of my lamp support; and

Fig. 6, what may be designated as a front view of said basic section bent into requisite shape;

Fig. 7, is an elevation of the upper end of the part shown in Fig. 6; and

Fig. 8, is an elevation of the lower end thereof;

Fig. 9, is a front view of the two sections 65 of the support as assembled for use, and fully extended as related to each other;

Fig. 10, is a rear view of the parts as shown in Fig. 5; and

Fig. 11, a side elevation thereof; 70

Fig. 12, is a central longitudinal section taken upon plane of line 8—8 Fig. 5;

Fig. 13, is an elevation of the upper end of my support;

Fig. 14, is an elevation of the lower extremity thereof. 75

The lower basic or socket member B, or section of my extensible lamp support is formed from a single blank of sheet metal, stamped into substantially the shape shown 80 in Fig. 5, and is then bent up into tubular form as shown in the subsequent figures of the drawings. Said blank B, is formed with lugs b, b, which are inturned for the purpose of maintaining the alignment of the adjustable section A. The lower part of the blank B, is also formed with the lateral extensions b', b', which are inturned to form the tubular socket b², which is internally screw threaded as shown in Fig. 12, for attachment 85 to the usual fixture, not shown.

The adjustable nipple section A, is formed with lateral extensions a, a, which on being inturned form the tubular nipple a', the upper end of which is peripherally screw threaded for engagement with an electric candle lamp in the usual manner. Said adjustable nipple section A, is also formed with the lateral tongues a³, a⁴, at its lower extremity which, on being inturned, acts as 90 stops to prevent the separation of the two sections A, B, when fully extended as related to each other as shown in Figs. 9, 10, 11 and 12 of the drawings, and more particularly in Fig. 9 thereof. 100

S, is a set screw engaging with a thread in the basic section B, and bearing against the adjustable nipple section A, as shown more particularly in Fig. 12 of the drawings. This screw is preferably formed with 110

a knurled head to facilitate manipulation, although I do not wish to limit myself in this respect, as other forms of set screws may be substituted if desired.

5 It will be noted, of course, that the adjustable nipple section A, when in tubular form, is of less diameter than the tubular diameter of the basic section B, so as to fit slidably therein.

10 My present construction and arrangement of parts is designed to simplify, cheapen and improve that set forth in my aforesaid concurrent application Serial No. 612,928. A practical advantage obtained by 15 my present structure is, dispensing with the necessity for slotting the lower basic section, and in having the set screw S, bear only against the nipple section A, thereby acting in conjunction with the lugs b, b, to 20 retain the sections in the requisite relative positions.

Another important advantage obtained by my present construction is dispensing with the lateral bracket arms on both sections of 25 the holder, and forming the nipple end socket screw threads directly on their respective parts. Furthermore by the use of the binding screw S, in conjunction with the retaining lugs b, b, I am enabled to attain a 30 greater extent of adjustment between the parts. Another advantage in this connection is convenience of access to the set screw S.

By my present invention I attain a maxi-

mum of simplicity and cheapness of construction while facilitating manipulation.

It is to be noted in this connection that, aside from the set screw S, my present structure is free from protuberances, with both sections in axial alignment; that the 40 parts may be die-formed exclusively, excepting only the cutting of the screw threads; and that the whole structure, considered in a unitary sense, is stronger, more rigid and substantial than heretofore.

45 What I claim as my invention and wish to secure by Letters Patent is:

As an article of manufacture, an adjustable support for electric lamps of the character designated, comprising a basic socket 50 member formed of a single piece of sheet metal inturned into tubular form, and internally screw threaded at its lower extremity and formed with inturned lugs at the other extremity, and an adjustive nipple 55 member formed of a single piece of sheet metal inturned into tubular form, and externally screw threaded at its upper extremity and formed with retaining lugs at its lower extremity, together with a binding 60 screw in threaded engagement with the basic section and bearing against the adjustive nipple section, for the purpose and substantially in the manner set forth.

SIDNEY M. ISRAEL.
